UNITED STATES PATENT OFFICE.

STEPHEN D. BAKER, OF NEW YORK, N. Y.

DESIGN FOR A RAZOR-BLADE CONTAINER.

Application filed July 1, 1926. Serial No. 18,222. Term of patent 14 years.

To all whom it may concern:

Be it known that I, STEPHEN D. BAKER, a citizen of the United States, residing in New York, in the county and State of New York, have invented a new, original, and ornamental Design for Razor-Blade Container, of which the following is a specification, reference being had to the accompanying drawing, forming part thereof.

The figure is a perspective view of a razor blade container showing my new design.

I claim:

The ornamental design for a razor blade container, as shown.

STEPHEN D. BAKER.
